US00D812631S

(12) **United States Design Patent** (10) **Patent No.:** **US D812,631 S**
Pleva et al. (45) **Date of Patent:** **** Mar. 13, 2018**

(54) **DISPLAY SCREEN WITH GRAPHICAL USER INTERFACE**

(71) Applicant: **Aetna Inc.**, Hartford, CT (US)

(72) Inventors: **Lukas Pleva**, Chicago, IL (US); **Richard C. Ekelman**, Chicago, IL (US)

(73) Assignee: **Aetna Inc.**, Hartford, CT (US)

(**) Term: **15 Years**

(21) Appl. No.: **29/562,139**

(22) Filed: **Apr. 22, 2016**

(51) LOC (11) Cl. **14-04**

(52) U.S. Cl. **USPC D14/486**

(57) **CLAIM**

The ornamental design for a display screen with graphical user interface, as shown and described.

DESCRIPTION

The FIGURE is a front elevation view of a display screen with graphical user interface showing my new design. The broken line showing of a display screen with graphical user interface is included for the purpose of illustrating portions of the article and form no part of the claimed design.

1 Claim, 1 Drawing Sheet

Why Total Cost is Important		
What will each plan really cost you, for the year? When picking a health plan, it's easy to focus on just a few numbers — like the premium, the deductible, or the cost of an office visit. These days, most plans are too complicated to just focus on a few numbers. A better approach is to start with the premium, and then add on all sorts of ALL your projected medical and prescription expenses for the year. That's what we call the Total Cost. The tricky part is actually calculating that estimate of all your medical and prescription expenses. Usually, you have some pretty accurate tools here to do that. (See, there's a lot of a range.)		
How do you ESTIMATE the TOTAL COST for a health plan?		
Annual Costs for \$100 Premium		
Minimum Total Cost (Premium x 12 Months) \$1,200.00 An estimate of how much you would pay if you never used any health services — or if you only used services 100% covered by the plan.	Your Estimated Total Cost Estimate by Out-of-Pocket Costs Use Aetna's to calculate a personalized estimate of how much you might spend on out-of-pocket care next year.	In-Network Maximum Total Cost (Annual Premium + Out-of-Pocket Max) \$6,000.00 An estimate of how much you would pay if you incurred a very high amount of medical expenses.
Close		

Why Take Credit Insurance? What would a client do, if it's aware of threats on just a few numbers? Is the insurance the insurance, or the rest of the offices that fall under their roof, these offices are not concerned in just threats to a few numbers. A bigger impact will be to start with the protection, does that mean that the companies of all, that you've insured and presented insurance for the year. The answer is called the total cost. The total cost is actually calculating the threats of all your medical and insurance expenses. (In fact, you have some pretty insurance costs here in the back, like a lot of stuff.)	How do you ESTIMATE the TOTAL COST for a health plan?	Annual Premium Annual Premium ✓ Your Estimated Total Cost Estimate My Cost of Health Care Minimum Total Cost (Premium x 12 Months) Any combination of these threats you need to pay in your health care every year: Services - or a few, they want services from companies like this plan.	In-Network Maximum Total Cost (Annual Premium + Out-of-Pocket Max) Any combination of these threats you need to pay in your health care every year: Services - or a few, they want services from companies like this plan. Costs
